UNITED STATES PATENT OFFICE.

JOHN CLARK, OF WILLIAMSBURG, NEW YORK.

MODE OF OPERATING WINDOW-BLINDS.

Specification of Letters Patent No. 22,625, dated January 18, 1859.

To all whom it may concern:

Be it known that I, JOHN CLARK, of Williamsburg, in the county of Kings and State of New York, have invented a new and useful Improvement in Window-Blinds; and I do hereby declare that the following is a full, clear, and exact description of the same, reference being had to the annexed drawings, making a part of this specification, in 10 which—

Figure 1, is a side or face view of a window blind having one of its stiles bisected or portion of it removed in order to show my invention. Fig. 2, is a section of the 15 stile above referred to taken in the line x, x , Fig. 1.

Similar letters of reference indicate corresponding parts in the several figures.

This invention relates to an improved 20 mode of operating the slats of the blind as hereinafter fully shown and described, whereby many advantages are obtained over the old modes or over all those that have come under my observation, to wit, the blind 25 having a far neater appearance, more durable, less liable to get out of repair and the slats more readily adjusted, the cost of construction not being materially if at all enhanced.

30 To enable those skilled in the art to fully understand and construct my invention I will proceed to describe it.

A, B, Fig. 1, represent the two stiles of a window blind, a , being the upper and b , 35 the lower cross rail.

C, are the slats of the blind. The slats are constructed of the usual form, provided with tenons c, c' , at their ends, the tenons being fitted in the stiles A B, and allowed 40 to turn freely therein.

The tenons c' , of the slats C, are fitted in the stile B, and each tenon c' , has a spiral toothed flanch d , placed on it, or an ordinary pinion will answer the same purpose.

45 In both drawings spiral toothed flanches are shown instead of pinions. The form of these flanches are clearly shown in Fig. 1.

In the stile B, a rack bar D, is fitted or placed longitudinally and allowed to slide 50 freely up and down therein. Into this rack bar the flanches d , gear as shown plainly in both figures. The lower part of the rack bar has teeth e , formed on it at one side and

into the teeth e , a pinion f , gears. The pinion f , is placed on a spindle or arbor g , 55 which passes into the lower part of the stile B, and has a knob h , on its outer end, the inner end of the arbor g , being stepped or having its bearing at i , as shown in Fig. 2, the knob h , being at the inner side of the 60 blind. At the inner side of the blind a projection j , is attached through which the arbor g , passes, and k , is a pin which is attached by a chain l , to the lower part of the blind, said pin forming a lock to the arbor 65 or spindle, preventing it from turning by passing it, the pin, when desired through the projection j , into the arbor or spindle, a hole m , being made in the arbor to receive the pin. 70

From the above description it will be seen that by turning the knob h , the rack bar D, will be actuated and the slats C, opened and closed or turned as desired. The friction attending the movement of the working 75 parts is sufficient to prevent any casual movement of the slats and the slats may be secured in a closed state so that they cannot be turned at the outer side of the blind, by inserting the pin k , in the spindle or arbor g. 80

I would remark that the arbor g , may project through the knob h , and have a square i' , formed on it to receive a key which may be passed through the lower rail of the window sash and thereby permit the 85 slats C, to be adjusted without raising the window sash. I would also remark that when the flanches d , are used or employed the rack bar D, is provided with a curved sunken gear j , to receive the toothed 90 flanches d . When however pinions are used a simple straight rack is attached to the bar D.

By the above invention the usual slat rod is dispensed with, a clear unobstructed 95 space being obtained in front of the slats. The slats may be adjusted with facility far more so than by the slat rod or all other modes of adjustment with which I am acquainted. The blind by my improvement is 100 also rendered more durable, the slats are not liable to be split or injured by being turned as is the case where the slat rod is employed. The blind as a whole has a far neater appearance than usual. 105

Having thus described my invention what
